UNITED STATES PATENT OFFICE

PETER B. MCCRAKEN, OF OAKLAND, CALIFORNIA, ASSIGNOR TO CARL P. JONES AND
CATHERINE PAYNTER, BOTH OF GRASS VALLEY, CALIFORNIA

ADJUSTABLE SPLINT

Application filed May 25, 1931. Serial No. 539,739.

This invention relates to surgical appliances, especially those adapted for reducing fractures of the lower limbs and hips.

It consists in the novel combination and arrangement, hereinafter described, of an adjustable splint, comprising a pair of anchor members to be fixed, one to the broken limb, and the other to the sound limb; a pair of axially adjustable tie-members pivotally connecting the anchor members; and an axially adjustable setting-member pivotally connecting the upper end of one of the anchor members with the lower end of the other anchor member.

The object of the invention is to provide a simple and effective splint of the type which employs the sound limb in counter-resistance to the tension on the broken limb.

In the accompanying drawings, to which reference is made, the appliance is shown in its preferred form, it being understood that changes may be made without departing from the spirit of the invention as defined in the claims hereunto appended.

In the drawings,

Fig. 1 is an elevation of the splint, the full lines showing it in normal shape ready to be initially adjusted and applied, and the dotted lines showing its shape after being set.

Fig. 2 is a fragmentary detail looking down on top from the line 2—2 of Fig. 1.

Fig. 3 is a front elevation showing in full and dotted lines a modification in direction of the setting-member.

Fig. 4 is a view showing the application of the device to the limbs of a patient.

1 is the anchor member for the broken limb, and 2 is the anchor member for the sound limb. These members are rigid plates of suitable dimensions adapted for fixed incorporation within casts applied to the limbs of the patient.

Upon the inner face of each anchor member near the upper and lower ends, are ears 3 to which are pivotally fitted by mill-headed pins 4, the coupling nuts 5.

Between the upper pair of nuts 5 is fitted the upper tie-member 6, the ends of said member being provided with right and left

hand threads, respectively, for engaging the correspondingly threaded nuts.

Upon the tie-member 6 is a finger grip 7 whereby said member may be conveniently turned on its axis, with the desired effect of determining the initial separation of the upper ends of the anchor members.

Between the lower pair of nuts 5 is fitted the lower tie-member 8 which consists of two aligned sections, one right-hand threaded and the other left-hand threaded, the adjacent ends of the two sections being fitted within a correspondingly threaded turn-buckle nut 9, thus providing for the initial separation of the lower ends of the anchor members.

The pivot pin 4 at the upper end of one of the anchor members and at the lower end of the other anchor member are long enough to pivotally receive the coupling-nuts 10 in which are fitted the aligned sections of the setting-member 11, said sections being right and left-hand threaded, respectively, and carry at their adjacent or meeting end the turn-buckle nut 12.

Although the appliance as a whole, in its simplicity and effectiveness is adapted for use, regardless of whether said setting-member 11 extends from the upper end of the broken-limb anchor to the lower end of the sound-limb anchor, as shown in Fig. 3, or extends from the upper end of the sound-limb anchor to the lower end of the broken-limb anchor as shown in Fig. 1, the preferred arrangement is the latter, wherein, by a lengthening of the setting-member, a push is exerted on the broken-limb to extend it, rather than a pull, as would be the case in the former arrangement under the shortening of the setting-member.

In applying and using the device, reference is now made to Fig. 4. The initial separation of the anchor members having been determined and the necessary adjustments made by means of the upper and lower tie-members 6 and 8, the anchor member 1 is fixedly incorporated in a cast 13 applied to the broken-limb 14, while the anchor member 2 is fixed in a cast 15 on the sound-limb 16.

Thereupon, the turn-buckle nut 12 is 100

turned in a direction to lengthen the setting-member 11 by the separation of its aligned sections, in case the form of Fig. 1 be used, or by the shortening of said member if the form of Fig. 3 be adopted, so that the general frame changes shape as indicated by the dotted lines in said figures, with the effect of applying stretching tension to the broken limb, with counter resistance from the sound limb.

10 I claim:—

1. An appliance for reducing fractures, comprising a pair of anchor members adapted for fixation, one to the broken limb and the other to the sound limb; a pair of tie-members pivotally connecting said anchor members above and below; and an axially adjustable setting-member pivotally connected with the upper end of one anchor member and with the lower end of the other anchor member.
- 15 2. An appliance for reducing fractures, comprising a pair of anchor members adapted for fixation, one to the broken limb and the other to the sound limb; a pair of axially adjustable tie-members pivotally connecting said anchor members above and below; and an axially adjustable setting-member pivotally connected with the upper end of one anchor member and with the lower end of the other anchor member.
- 20 3. An appliance for reducing fractures, comprising a pair of anchor members adapted for fixation, one to the broken limb and the other to the sound limb; a pair of tie-members pivotally connecting said anchor members above and below; and an axially adjustable setting-member pivotally connected with the upper end of the anchor member to be fixed to the sound limb and with the lower end of the anchor member to be fixed to the broken limb.
- 25 4. An appliance for reducing fractures, comprising a pair of anchor members adapted for fixation, one to the broken limb and the other to the sound limb; a pair of axially adjustable tie-members pivotally connecting said anchor members above and below; and an axially adjustable setting-member pivotally connected with the upper end of the anchor member to be fixed to the sound limb and with the lower end of the anchor member to be fixed to the broken limb.

50 In testimony whereof I have signed my name to this specification.

PETER B. McCRAKEN.
